UNITED STATES PATENT OFFICE.

WILLIAM C. MILLER, OF MORETOWN, VERMONT.

AUTOMATIC TRAIN-PIPE COUPLING.

1,143,984.

Specification of Letters Patent. Patented June 22, 1915.

Application filed March 4, 1915. Serial No. 11,960.

To all whom it may concern:

Be it known that I, WILLIAM C. MILLER, a citizen of the United States, residing at Moretown, county of Washington, and State 5 of Vermont, have invented a certain new and useful Improvement in Automatic Train-Pipe Couplers, of which the following is a specification.

This invention relates to automatic coupling and uncoupling means for train pipes both air and steam, or air alone, as desirable and it is to be applied either to railway cars or to other railway vehicles.

The invention is for the purpose of meeting 10 the conditions set forth in the acts of Congress which require railroads to be equipped with automatic couplers so constructed that the coupling and uncoupling can be effected without requiring employees 15 to go between and below the cars for this purpose. It is also designed to meet the further requirements of the law, that freight cars shall be equipped with power brakes operated from the engine to be effective 20 upon each car of the train.

The invention embodies a novel arrangement of parts for quickly and securely coupling the train pipes together when the cars are coupled, and for automatically releasing the said train pipe coupling means when the cars are uncoupled and move away 25 one from the other.

When my invention is to be applied to passenger cars, the train pipe coupler is 30 provided with connections for both the train air pipes and the train steam pipes; and when the invention is applied to freight cars, only train air pipe connections are provided. It is also obvious that pipes when 35 required for use in operating the signals or other similar devices, may also be applied to my train pipe coupler. In either case, my invention in its broad aspect is not changed.

The invention consists in the combination 40 and arrangement of parts hereinafter described and claimed.

Referring to the drawings, which form a part of this specification; Figure 1. is a side view in coupled position of my invention 45 shown applied to the ends of contiguous railway cars, parts of the car structures and other fixed parts being shown in section, the coupling means being shown in elevation; Fig. 2. is a plan view also in coupled position with portions in section and other parts broken away, so as to more readily

show the construction of the coöperating parts; Fig. 3. is a side elevation of the invention, the parts thereof being in the position shown in Fig. 2., one of the flanges 50 broken away so as to show more distinctly, parts which would otherwise be hidden from view; Fig. 4. is a sectional view taken on line 4—4 of Fig. 3; Fig. 5. is a sectional view taken on line 5—5 of Fig. 1; Fig. 6. 55 is a sectional view of a detail.

In the drawings, like reference characters refer to like parts in the several views.

A represents in section the conventional structure of the platform at the end of one 60 car and B is a similar view of the end of the platform of a contiguous car.

C is the entire car coupling mechanism, the operative parts of which necessary to disclose the construction and operation of 65 my invention, will be hereinafter described, and D is the train pipe coupler which embodies my invention.

A coupler head 1 constructed in the desired form is provided with a projecting 70 shank 2, the free end of which is pivoted by a bolt 3 to a U shaped yoke 4 mounted to slide in a bracket 5. The shank 2 also is mounted to slide in a bracket 6 which is secured to the beam 7 of the car platform. 75 The bracket 5 is secured by bolts or other suitable means to the under-side of the car platform, and in the sides 9 of which are formed slots or grooves 8. Cross bars 10 and 11 are so fitted in the bracket 5 that 80 their ends rest in and slide within the slots or grooves 8. The buffer spring 13 is placed between the bars 10 and 11 which acts as a buffer when the cars are coupled and which operates to move the coupler head 1 in the 85 direction of the arrow when the cars are uncoupled and when they move away from each other.

The construction just described is more or less conventional and a similar construction is indicated on the car B by the parts 1', 2', 3', 4', 5', 6' and 7'.

A fixed hanger or projection 15 is rigidly secured to the shank 2 on car A, and a similar rod or projection 15' is similarly placed 90 upon the shank 2' on car B.

In the further description of my invention it is to be understood that the train pipe couplers are substantial duplicates of each other and the construction as applied 95 to each car will now be specifically described, using certain reference numerals

to refer to parts of the coupler secured to one car and the same reference numerals primed to refer to like parts of the co-operating coupler upon the adjacent car.

Brackets 20 and 20' are rigidly secured to the under-side respectively of the cars A and B and are provided with ways 21 and 21', 22 and 22' in which the shanks 23 and 23' at one end of which are secured the train pipe coupling heads 24 and 24', are mounted to slide. Fixedly secured to the shanks 23 and 23' of the train pipe coupling bars are lugs or collars 25 and 25'. Springs 26 and 26' surround the shanks 23 and 23' and abut against the collars 25 and 25' and fixed ends 27 and 27' of the brackets 20 and 20'.

Secured to the inner ends of each bar 23 and 23' adjacent the coupling faces thereof are hood shaped devices, the outer ends of which are expanded into funnel shaped flanges 30 and 30' and the inner ends 31 and 31' are tubular in shape and form pockets for the reception of the inner ends 23 and 23' of the coupling heads. The inner end of the tubular portions 31 and 31' are constructed with perpendicular edges 33 and 33'. Spring latches 34 and 34' are secured by screws or in any other suitable manner, at their inner ends, to the innermost ends of the bars 23 and 23'. At the outer end of the spring latches are enlarged heads 35 and 35' which are provided with inclined or cam surfaces 36 and 36' which are joined to the spring shank by perpendicular edges or notches 37 and 37'. Pivoted to the bars 23 and 23' are a series of levers 40, 41 and 40', 41', the upper levers 40 and 40' being secured midway of the lever 41 and 41' by pivotal connecting rods 42 and 42'. Springs 43 and 43' are secured to the levers 41 and 41' and to fixed lugs 44 and 44' extending from the bars 23 and 23'. Guide brackets 45 and 45' are secured to the bars 23 and 23' to hold the levers 40 and 40' in place and to guide the same when operated. In each coupler head are secured pipes 50 and 50' for the passage of air and pipes 51 and 51' for the passage of steam. These pipes are provided with unions as shown by means of which they may be connected together and extended in any desired direction. Secured to the ends of the pipes 50 and 50' and 51 and 51' are rubber or flexible pipes of any approved construction indicated at 52 and 52'. In the faces of the coupler heads surrounding the contiguous openings for the air and steam pipes are rubber gaskets 53 and 54, to insure the steam and air openings having a tight fit at the meeting joints.

Suitable valves are placed in the various pipes at any approved position in order to control the delivery of the operating fluids as desired.

The operation of my invention will now be described. When the parts are all in the positions shown in Fig. 1, the cars are coupled together and the train pipes are also coupled together. On the uncoupling of contiguous cars, the strain will be released from the coupler heads 1 and 1' and the springs 13 and 13' will operate to move the respective coupling heads in the direction of the arrows, thereby moving the bars or lugs 15 and 15' also in the direction of the arrows, thus causing them to strike against the upper and free ends of the levers 41 and 41' thereby moving them about their pivots in the general direction of the arrows. When the levers are so moved the connecting rods 42 and 42' pull the free ends of the levers 40 and 40' in a similar direction thereby causing them to wipe over the inclined surfaces 36 and 36' of the enlarged heads 35 and 35' of the spring latches 34 and 34', thereby releasing the latches from the free ends of the parts forming the pockets 31 and 31'. When the latches are released, the shanks 23 and 23' are free to move away from each other upon the separation of the contiguous cars. When it is desired to couple two cars together and that operation is done in the usual way, the respective ends of the shanks 23 and 23' enter respectively the flanged funnels and through the pockets as shown, the buffing strains being taken up by the springs 26 and 26'. The shanks or bars 23 and 23' enter through the funnels and pockets a sufficient distance to enable the heads of the latches 24 and 24' to co-act and assume a latching position against the inner edges of the tubular portions 31 and 31' which form the pockets. The parts are so adjusted that when this occurs, the steam and air openings or ports meet in proper positions, so that the respective fluids may pass from car to car as desired.

My device is made of suitable metal to meet the conditions of the laws and the rules governing railroad equipment constructions.

While I have shown certain features of my invention in the accompanying drawings, it is to be understood that said drawings are merely illustrative, and that I am not confined to what is there shown and herein described in connection therewith, except as may be specifically set forth in the claims.

Having now described my invention, what I claim as new and desire to secure by Letters Patent, is:

1. A train-pipe coupler head having a plurality of fluid ports therein, means to latch the same to a counter-part coupler head, also having fluid ports therein, the fluid ports of one head co-acting with the ports of the other head and means independent of

and separate from the train pipe coupler head to unlatch the coupler heads upon the uncoupling of the cars.

2. A train-pipe coupler head having a fluid port in its face, a conduit extending from the ports through the head thereof, a latch for locking one coupler head to another, spring controlled means mounted upon the car independent of and separate from the train pipe coupler head operable upon the uncoupling of the car coupler to release the latch which holds the train-pipe coupler heads together,
3. A train-pipe coupler head having a funnel shaped flange thereupon to receive the adjacent coupler head and in which it is inserted, an extension from the flange forming a pocket for the adjacent coupler head, a latch on one coupler head engaging the pocket, and spring actuated means constructed to have a movement independent of the movement of the car and independent of the movement of the train pipe coupler head operable upon the uncoupling of the car to release the latch.
4. A train-pipe coupler head, means for latching the same to a counter-part coupler-head and spring means operable independently of the train pipe coupler head upon the unlatching of the coupler-head to release the latch.
5. In a device of the class described, a train pipe coupler head, means for latching the same to a counter part coupler head, means mounted upon the train pipe coupler head to unlatch the latch, means independent of the train pipe coupler head mounted to have a reciprocatory movement with respect thereto arranged to operate the unlatching means during said independent reciprocal movement.

In witness whereof I have hereunto set my hand at Moretown, county of Washington and State of Vermont, this 26th day of February, 1915.

WILLIAM C. MILLER.

In presence of—

HERBERT G. WARD,
